DESIGN FOR A JEWELRY FINDING

Victor Silson, New York, N. Y.

Application June 26, 1943, Serial No. 110,540

Term of patent 3½ years

To all whom it may concern:

Be it known that I, Victor Silson, a citizen of the United States of America, residing in New York city, county of New York and State of New York, have invented a new, original, and ornamental Design for a Jewelry Finding, of which the following is a specification, reference being had to the accompanying drawing, forming part thereof.

Fig. 1 is a plan view of a jewelry finding showing my new design.

Fig. 2 is an edge view thereof.

The dominant feature of my new design resides in the portions shown in solid lines.

I claim:

The ornamental design for a jewelry finding, substantially as shown and described.

VICTOR SILSON.
